UNITED STATES PATENT OFFICE.

LOUIS WILDHAGEN, OF BAILEY'S HARBOR, WISCONSIN, ASSIGNOR TO HIMSELF AND JOHN MILLIDGE, OF SAME PLACE.

HAME-FASTENER.

SPECIFICATION forming part of Letters Patent No. 434,967, dated August 26, 1890.

Application filed December 2, 1889. Serial No. 332,276. (No model.)

To all whom it may concern:

Be it known that I, LOUIS WILDHAGEN, of Bailey's Harbor, in the county of Door and State of Wisconsin, have invented a new and useful Improved Hame-Fastener, of which the following is a full, clear, and exact description.

My invention is an improvement in the class of hame-fasteners which are adapted for adjustment in length and for detachable connection with the hames.

The features of the improvement are as hereinafter described and claimed.

Reference is to be had to the accompanying drawings, forming a part of this specification, in which similar letters of reference indicate corresponding parts in all the figures.

Figure 1 is a side view of the hame-fastener, with parts extended and attached to the lower ends of a pair of hames. Fig. 2 is a side view of the hame-fastener, an extensible portion being shown in dotted lines. Fig. 3 is a bottom plan view of the hame-fastener. Fig. 4 is an enlarged detached sectional view of a coupling-latch hook, duplicates of which are used to attach the ends of the device to a pair of hames. Fig. 5 is an enlarged perspective view of a detached coupling-latch hook, and Fig. 6 is a transverse section of the hame-fastener, taken on the line 6 6 in Fig. 2.

One main portion of the hame-fastener consists of a shackle-bar A, which is made extensible by constructing it in two pieces a a'. These pieces are similarly curved and adapted to have sliding connection with each other by providing the piece a with hooking or inwardly-inclined flanges a² on its edges that are parallel, between which flanges the male portion a' is slid, thus affording a dovetail engagement for these pieces that prevents lateral displacement. On the male piece a' a hook b is formed, which curves downwardly, having its terminal b' enlarged and rounded to produce ears for a hinge-joint thereon, which ears are completed by longitudinally slotting the hook through its body near the center of width.

A curved leaf-spring c is located in the slot of the hook b, conforming in shape thereto, one end being secured to the hook at c', the

other having engagement with the shoulder c², formed on the latch-toe d, which is pivoted at its end d' to the ears b'. The spring c is expanded when introduced and bears forcibly upon the shoulder c², which will rock the latch-toe d, so that an integral flange d² will engage its adjacent shoulder d³ with the upper surface of the hooks b n.

The portion a' of the shackle-bar A is perforated at e for the reception of the locking-pin e', which is diametrically enlarged at e², forming a head therefor that seats upon the exterior surface of the portion a when the pin is depressed by contact therewith of the leaf-spring e³, which is fastened by its opposite end 65 to the shackle-bar, the upper or head portion e² of the locking-pin e' being slotted to receive the free end of the leaf-spring and prevent it from displacement. A guard-hook e⁴, which projects from the shackle-bar in alignment with the spring e³ near its free end, serves to limit the vertical movement of the locking-pin e', when it is disengaged from the male piece a' of the shackle-bar.

A series of spaced indentations or socket holes e are formed in the male piece a' of the shackle-bar A, which are longitudinally aligned and adapted to register with the locking-pin e' when the two portions of the shackle-bar are adjusted so as to permit this. 70 By the provision just described the length of the shackle-bar can be altered to suit the desired separation afforded to the lower ends of hames it connects.

On the female portion a of the shackle-bar 85 A the hook h is formed or secured near the end of the same oppositely to the guard-hook e⁴ that it is aligned with, its hook-lip h' extending toward said guard-hook. (See Fig. 1.)

The shoe-piece B, which forms the other 90 main portion of the hame-fastener, consists of a piece channeled throughout its length, with the exception of a curved cap-plate i, that is integrally formed with the other part, which latter is an arched trunk having parallel 95 walls that are shaped on their free edges to lie closely upon the portion a of the shackle-bar A.

On the end of the shoe-piece B which is opposite to the cap-plate i parallel lugs i' are 100

produced on its walls by cutting away the connecting-arch that joins said walls and shaping the detached portions so as to afford suitable supports for a transverse pin *k*, which can be seated in the hook *h*, as shown in Figs. 1 and 2.

A straddle-loop *m* is pivoted at its ends *m'* to the side walls of the shoe-piece *B*, which points of connection are opposite and near the free edges of the side walls, and consequently above the point *k* of hooked attachment of the shoe-piece *B* to the hook *h* on the shackle-bar *A*. As the hook *h* has its edge sloped to produce an inclined plane, as *h²*, draft-strain applied to the cross-bar *m²* of the straddle-loop *m* will hug the shoe-piece *B* tightly against the shackle-bar *A*.

Upon the loop *m* a coupling-latch hook *n* is loosely secured, so that it may vibrate freely thereon, said hook being constructed to duplicate in form and operation the hook *b*, whereby secure latching-connections are provided for the hame-fastener at each end thereof, which will automatically lock fast to the ordinary looped ends of harness-hames *C* when applied thereto in an obvious manner.

Owing to the peculiar manner of pivoting the straddle-loop *m* on the shoe-piece *B* and its position relatively to the point of hooked connection effected between the shoe-piece and shackle-bar *A*, when the parts are adjusted as shown in Fig. 1, the hooks *b* and *n* being attached to the lower ends of the hames *C*, a swinging movement of the shoe-piece on its pin *k* will convert it into a lever having toggle-joints, thus enabling an operator to forcibly draw the separated hooked ends of the hame-fastener toward each other until the edges of the shoe-piece and points of pivotal connection of the straddle-loop therewith are above the pivot-point *k*, which will lock the parts securely owing to the slightly-elastic nature of the collar upon which the hames are located.

Any desired adjustment for length may be effected by means of the extensible shackle-bar *A*.

The device is constructed mainly of malle-

able iron or low-grade steel, and can therefore be produced very cheaply.

Having thus described my invention, what I claim as new, and desire to secure by Letters Patent, is—

1. In a hame-fastener, the combination, with the shoe-piece *B*, the pivoted straddle-loop *m*, its latch-hook *n*, the two sliding portions composing the body of the shackle-bar, the same having terminal hooks and one of said portions provided with perforations *e*, of the locking-pin *e'*, having an open slot in its head, and the leaf-spring *e³*, attached to one of the shackle-bars and its free end resting in the slot of said head, as shown and described.

2. In a hame-fastener, the combination, with the shoe-piece *B*, the pivoted straddle-loop *m*, its latch-hook *n*, and the two sliding portions composing the body of the shackle-bar, the same having terminal hooks and one of them provided with perforations *e* and the other with the guard-hook *e⁴*, located on its under side, of the locking-pin *e*, having a slotted head and arranged in vertical alignment with the aforesaid hook, and the leaf-spring *e³*, attached to one of the shackle-bars and its free end resting in the slot of said head, as shown and described.

3. In a hame-fastener, the combination, with an extensible shackle-bar composed of two sliding portions that can be locked at different points by a pin-and-socket connection, and a coupling-hook having a spring-actuated latch-toe, of an arched shoe-piece which is pivotally engaged with a projecting hook formed on the extensible shackle-bar, a straddle-loop pivoted at the ends of its limbs to the walls of the shoe-piece near one end of said shoe-piece and out of line with its hooked connection on the shackle-bar, and a coupling-latch hook that mates the hook on the shackle-bar and is loosely attached to the cross-bar of the straddle-loop, substantially as set forth.

LOUIS WILDHAGEN.
